Edward J. Kuntze of New York, N.Y.

Letters Patent No. 2091-Dated June 8-1865.

Design for a Statuette of Shakespeare.

The schedule referred to in these letters Pat. and making part of the same.

To all whom it may concern:

Be it known that I, Edward J. Kuntze, of the City of New York, in the County of New York and State of New York, have invented or produced a new and original design for a Statuette of Shakespeare, and I do declare that the following is a full and exact description of the same.

The figure of William Shakespeare, dressed in the costume of his time, rests lightly with his right hand which holds a gun, on the top of a tree-trunk; a cloak, thrown over his left arm gathers in folds behind, the other end is suspended on the tree-trunk, the left hand holds a tablet upon which his attention is fixed. At his feet, leaning against the tree, is the figure of "Puck" seated, his legs crossed and holding a laurel wreath. All of which is clearly seen in the accompanying photographs and what I claim as my invention or production and desire to secure by Letters Patent is the design of a Statuette of Shakespeare, as shown and described.
